STRINGED MUSICAL INSTRUMENT

Filed March 11, 1929

Fig. 1

UNITED STATES PATENT OFFICE

GEORGE D. BEAUCHAMP, OF LOS ANGELES, CALIFORNIA

STRINGED MUSICAL INSTRUMENT

Application filed March 11, 1929. Serial No. 346,009.

This invention relates in general to stringed musical instruments, and more particularly to an instrument of the guitar or banjo type.

An object of the invention is to provide an instrument of the character mentioned in which a single resonator or amplifier is provided, and which will be simple in construction, economical in manufacture, and which produces tonal values not capable of being produced in other stringed instruments of the same type.

Another object is to provide an instrument of small and convenient size having a single metallic resonator of conical form and improved means for connecting the resonator with the strings, whereby the vibrations from the strings may be more effectively transmitted to and amplified by the resonator, than by other means in use.

A further object is to provide in a stringed musical instrument an improved type of metallic resonator and bridge connecting the resonator with the strings.

Other objects may appear as the description progresses.

I have shown one form of device embodying my invention in the accompanying drawing, in which

Fig. 1 is a top plan view of an instrument.

Fig. 2 is an enlarged fragmentary transverse section of the same on line 2-2 of Fig. 1.

Fig. 3 is a sectional plan on line 3-3 of Fig. 2.

Fig. 4 is a fragmentary section of the bridge.

The body B of the instrument is of conventional form, and has a solid bottom 1, an open top 2, and a curved side 3. Any or all of said body members may be formed of wood, composition, or metal, and suitably attached together for providing a hollow resonant body.

The usual neck N is provided longitudinally of the body and has an extension 4 extending longitudinally through the interior of the body as shown in Figs. 2 and 3. Said neck carries a plurality of strings S, S etc., which are attached at their outer ends to the usual keys K, K etc., and the inner ends of the strings are attached to a metallic tail piece C overlying the top 2 of the body. The said top

2 has a circular opening 5, or said opening may be of any other suitable form, and it is covered by a detachable plate 6 with a central opening 7 therein.

An annular ring 8 of wood or metal is mounted internally of the body and is attached to the top 2 and the cover plate 6 by means of screws or brads 9. Said ring is shallower than the body of the instrument and may have attached to its lower edge by suitable means a thin metallic ring 10, which is supported at a plurality of points on posts 11, 11 etc., having their lower ends resting upon the bottom 1. The ring 10 also rests upon the neck portion 4 and has a large central opening 12 concentric with the opening 7 of the cover plate 6. The ring 10 projects inwardly from the band 8 so as to provide a ledge upon which the circular edge of a metallic resonator R is adapted to rest. Said resonator is of substantially conical form and is made of thin sheet metal, preferably aluminum, so thin in fact that it is readily flexible and yet sufficiently firm to maintain its shape when mounted in operative position in the instrument.

An annular bead 13 is formed at the outer edge of the resonator, which engages the upper side of the ring 10. Inwardly of the bead, the resonator is bent at 14 so as to provide a slightly angular portion in cross section to permit of the ready flexing and vibration of the metal.

Centrally of the opening 7 in the cover plate 6, and substantially in the plane of said plate, the upper portion 15 of the resonator is formed with an annular bead or ridge 16 therearound and the top of the cone is depressed internally of the bead. The plane of the strings S is substantially above the plate 6, and in order to transmit the vibrations from the strings to the resonator I provide a circular bridge member A which may have a flat base portion 17 adapted to rest upon the bead 16 and to be attached thereto by rivets 18.

The member A may also be provided with a transverse diametrically disposed rib 19 which may or may not be notched, for receiving the strings S, S etc. Thus the rib or bar

19 of the member A constitutes a bridge for holding the strings in tension, and said bar may be formed integrally with or apart from the member A as shown, for direct contact with the strings.

5 I have found that by the use of a single resonator and a circular tensioning member, as shown at A, the vibrations from the strings are readily transmitted to the resonator R and the resonator when so connected with the strings serves to substantially amplify the vibration set up in the strings, and the tonal qualities of the instrument are accordingly substantially improved.

15 I prefer to employ a guard 21 extended transversely of the instrument over the bridge A and attached at its ends 22, 22 by suitable means to the cover plate 6. Said cover plate is provided with a plurality of screened openings 23, 23 etc., from which the vibrations from the instrument emanate.

20 It will be observed that the resonator R is held in position by the tension of the strings and is not at any point secured to the supporting members. Due to this fact, by the removal of the cover plate 6, the members A and R may be readily replaced, removed, or repaired.

25 In the construction of an instrument of this character, I have found it important in order to transmit the vibrations from the strings to the resonator and to produce a maximum volume in the instrument, that the member A should be firmly held in contact with the resonator as at the bead 16 thruout the extent 30 of the annular portion 17. Accordingly, the member A is made of substantial diameter.

35 Heretofore, instruments of this type have been constructed with a plurality of resonators of substantially smaller size than shown in the drawings relating to this particular device. Also, the bridge which connects the strings with the resonators has been either directly or indirectly connected with the apices 40 of the resonators at single points only. In this device, however, by the employment of a circular tensioning member A which engages the bead 16 or the cone for preferably the full extent of the circle of contact, the vibrations are more effectively transmitted to 45 the resonator R than would otherwise be possible, and a satisfactory instrument may be provided with a single resonator instead of a plurality of resonators.

50 It will be observed from the foregoing description and the consideration of the drawings of my invention, that I have provided a simple, compact, economical, and efficient musical instrument with amplified tonal 55 qualities unusual to instruments of this type.

60 I conceive it to be possible to modify the structure shown and described within the scope of the appended claims without departing from the spirit of my invention.

65 C3 What I claim is:

1. A guitar comprising a hollow body having an opening in the top thereof, an annular ring depending from the top and below said opening, a conical metallic resonator supported within said ring with its base 70 downwardly, a neck piece extending longitudinally from said body, strings attached to said neck piece and stretched over said body, and a circular bridge engaging the upper portion of said resonator at its inner side and said strings for holding the strings and the resonator in tension, whereby vibrations may be transmitted from the strings to the resonator.

2. A guitar as characterized in claim 1, 80 including a second ring engaging the lower side of said first mentioned ring and projecting inwardly therefrom for engagement with and adapted to support the base of said resonator.

25 3. A guitar as characterized in claim 1, including a cover plate mounted over the opening in said top and provided with a central opening concentric with the upper portion of said resonator, said bridge extending through the opening in said cover plate.

4. A guitar as characterized in claim 1, including a cover plate mounted over the opening in said top and provided with a central opening concentric with the upper 95 portion of said resonator, said bridge extending through the opening in said cover plate, a transverse guard member having a central portion elevated from the plane of said cover plate and overlying said strings and said bridge, and end portions bent downwardly and attached to said cover plate.

5. A guitar comprising a body having an opening in the top thereof and strings stretched thereover, a conical resonator supported in the body below said opening, means for supporting the strings in playing position over the top of said body, and a tensioning member engaging said strings and said resonator and having an annular portion 100 making annular contact with the resonator.

6. A guitar comprising a body, a conical resonator mounted therein, strings stretched over said body, and a bridge engaging said strings and having an annular portion making annular contact with said resonator for 115 tensioning the strings and transmitting vibrations from the strings to the resonator.

7. A guitar comprising a hollow body having an opening in the top, strings supported over said opening, a conical resonator mounted in the body and having an annular bridge receiving portion disposed adjacent said opening, and a bridge interposed between said strings and said resonator and engaging said annular portion, for the purpose 120 described.

8. A guitar comprising a hollow body having an opening in the top thereof, strings stretched over the said body and said open- 125

- ing, a conical resonator mounted in said body and having an annular bridge receiving portion adjacent said opening, and a bridge engaging said strings and said resonator and means for said strings embodying a member having an annular portion making annular contact with said resonator and engaging said strings. 70
- 5 having a circular base engaging the annular portion of said resonator for holding said strings in tension and for transmitting vibrations from the strings to the resonator. 75
9. A guitar comprising a hollow body, strings held thereon, a conical metallic resonator mounted within the body, and provided with a central annular bridge receiving portion formed by indenting the central portion of the cone, and a circular bridge contacting therewith throughout the extent of said annular bridge receiving portion and engaging said strings, whereby the resonator and the strings are held in tension. 80
10. A guitar comprising a hollow body having a central opening in the top thereof, strings supported over said opening, a conical metallic resonator supported in said body at its base with the apex uppermost and having its central portion conically formed with the base thereof uppermost to provide an annular bridge receiving portion adjacent said opening, a bridge mounted on said bridge receiving portion and engaging said strings for holding the strings and the resonator in tension. 85
11. A guitar comprising a hollow body having an opening in the top thereof, strings stretched over said opening, a single conical resonator mounted in said body and having its central portion disposed adjacent said opening, said central portion including an annular bridge receiving portion, and a bridge making annular contact therewith and engaging said strings for holding the resonator and the strings in tension. 90
12. A stringed musical instrument comprising a body, a resonator mounted therein and provided with a central depressed portion, means for supporting said resonator in operative position, strings stretched over said body, and means directly engaging said strings and said depressed portion for communicating vibrations from the strings to the resonator. 95
13. A guitar comprising a hollow body having an opening in the top thereof, a plate closing said opening and provided with a smaller opening therein, an annular partition within said body and depending from the top thereof and having its inner periphery corresponding to the margins of the opening in said body, a ring engaging the lower edge of said partition and extended inwardly from the inner periphery thereof forming a ledge, a conical resonator having its base mounted on said ledge and its upper portion positioned adjacent the opening in said cover plate, means for operatively supporting strings over the top of said body, and tensioning 100
